UNITED STATES PATENT OFFICE.

ROLAND V. RANDALL AND VICTOR E. RANDALL, OF BATTLE CREEK, MICHIGAN, ASSIGNORS OF ONE-THIRD TO BENJAMIN GWATKIN, OF BATTLE CREEK, MICHIGAN.

RAILWAY TIE.

Application filed October 5, 1920, Serial No. 414,849. Renewed May 23, 1923.

To all whom it may concern:

Be it known that we, ROLAND V. RANDALL and VICTOR E. RANDALL, citizens of the United States, residing at Battle Creek, in the county of Calhoun and State of Michigan, have invented certain new and useful Improvements in Railway Ties, of which the following description, taken in connection with the appended claims and accompanying drawings, forms a specification.

The present invention relates more particularly to railway cross-ties formed of material other than wood, such as metal, concrete or analogous material, the same to be formed in lengths suitable for the purpose.

A characteristic feature of the present invention is a slot longitudinal of a tie, within which rail anchoring bolts are adjustably secured.

20 In general, composite railway ties do not allow for minute adjustment of attachments for the rails they support, and in placing ties of this character in a roadbed great care must be exercised to place them so that 25 the rail-fastening mechanism carried by the ties will accurately engage the aligned rails they are to secure, whether in making replacements in a line of track previously built or in making new road.

30 This invention has among other objects to overcome the disadvantages enumerated, and to so construct a tie that the same may be installed in a roadbed either end to or either side up, and permit of a rail or rails being clamped thereto at other than predetermined points.

Another important object of the present invention is to provide means whereby the bolts for securing the clamps to the tie cannot 40 jar loose nor slide after having been anchored.

Another object of the invention is to so construct the rail clamps that when in operative position though a rail may wear 45 away its seat or bearing on the tie and permit a clamp to loosen vertically, yet said clamp will prevent outward movement of said rail and at all times prevent its anchor-bolt nut from turning on its seat, and the 50 consequent loosening of said bolt.

Other objects of the invention are, to provide a tie requiring nothing more than an ordinary track wrench to install the rail-fastening mechanism; and to provide a rail-securing mechanism positive in action, sim-

ple in construction and economical to manufacture.

The foregoing and other objects and advantages will be more fully comprehended by a study of the drawings taken in connection with the description referring thereto.

In the drawings, Figure 1 is a central longitudinal section of a rail-bearing block with a rail installed thereon showing a cross-section of one of the rail holding clamps.

Fig. 2 is a plan view of a rail-bearing block with a rail installed thereon, embodying the features of the block and rail fastenings shown in Fig. 1.

Fig. 3 is a perspective view of a modified form of a rail-bearing block.

Fig. 4 is a cross-section of Fig. 3, and it also shows a cross-section of Figs. 1 and 2 bisecting the block at a point between the 75 bolt receiving holes.

Fig. 5 is another modification of the rail-bearing block in perspective view.

Fig. 6 is a cross-section of the block shown in Fig. 5 on the line x.

Fig. 7 is a cross section of a block with an I-shaped bolt slot.

Fig. 8 is a detail perspective view of a rail-holding bolt, together with its washers and anchor-nut, and also a rail clamp and its fastening nut.

Like marks of reference refer to corresponding or equivalent parts throughout the different views, in which A represents rail-bearing blocks; B, railway rails; C, shims or seats of wood or other resilient material between the rail and blocks; D, portable metallic rail seat holders for retaining the rail seats in proper location on the rail blocks; E, clamping members engaging the rail-flanges on either side of the rail and secured by means of vertical bolts 1 extending upwardly through a longitudinal slot or slots 2 of a block A.

Referring to the rail-bearing blocks A: 100 these blocks may be formed of any material adequate for the purpose as, for instance, artificial stone. They might also include blocks or bearings of metal to accomplish the same purpose, but when blocks of artificial stone are used it is advisable that some binding and reinforcing element be introduced within the structure to insure a more stable article, and to this end we have shown loops and cross bars 3 and 4, respectively, 110

as embedded in the blocks. We are aware that metallic bars and loops have been employed for a like purpose in other structures, and we do not claim such means as new, but strongly recommend their use to accomplish the desired result.

Throughout the various modifications of the rail-bearing blocks shown, the characteristic feature for placing, adjusting and seating the anchor bolts 1 lies in the formation of a longitudinal slot (as 2) extending partially if not wholly the length of a block, and in either case forming a block so that offsets 5 of said slot will form shoulders against which the heads 6 of the bolts 1 may engage to prevent said bolts from pulling away from said blocks when in operative position.

When a slot extends the length of a tie, as shown in Fig. 3, it is preferable that the entrance for anchor bolts bisect the tie only from its top or operative face to insure stability thereto, but when a slot or slots are formed in a block and made to extend but a portion of its length, such slot or slots may be formed to extend either partially or wholly through said block. An example of a block formed with a slot extending but partially therethrough is shown in Fig. 1, and with slots extending entirely through blocks, in Figs. 6 and 7.

As shown in Figs. 1 and 2, the under-cut or offset sides near the bottom of the slot terminate with vertical pockets 7 opening at the top of the block. These pockets are of a breadth corresponding to the width of the shoulder extremities of the slot 2, and are for the purpose of admitting the heads of the anchor bolts 1.

In Figs. 5, 6 and 7, the slots 2 are formed to extend through a block from face to face, and if desired to anchor a bolt centrally of said block, the slot is widened to form offsets or shoulders 5 which will hold a bolt head when introduced within an end pocket 7 from either face of a block.

In the modified form shown in Fig. 7, in lieu of making an offset to the slot 2 centrally of the block for bolt head anchorages, it is preferred that channels (as 8) be formed in the faces of a block at least the depth of a bolt head and the slot be formed to intercept the said channels centrally. In the block shown in Fig. 5, two slots are formed, the same being separated by a cross-girt or bridge 9 centrally of the block, the top and bottom reinforcing loops 3 being connected with cross bars 4 to materially strengthen the blocks at this portion. A tie of this character while not permitting as great a latitude of adjustment as with a tie having a single long bolt-holding slot, will in a great majority of instances give perfect satisfaction, as for instance, in making tie installation in old road beds where renewals

are supplied. In such case the rails are properly lined up and even though a tie is not set in position for the rail to cross its exact center, a movement of a couple of inches either side from its center could be made with satisfactory results.

In the drawings we have shown an approved method of seating the rail on a resilient seat of wood held in place by a metallic frame, which is not a part of the present invention, it being understood that any approved means could be employed for seating the rail on the rail-bearing block. A rail B having been seated on a rail block in proper alignment, bolts (as 1-1) with the heads (as 6) downward are introduced into a slot or slots 2 of the rail block, and where the slot opens at the block ends said bolts are inserted. Where the bolt slots extend but a portion of the length of a block or tie, as shown in Figs. 1, 2, 5, 6 and 7, a bolt is introduced head downward within a pocket (as 7) and slid along the slot 2 into operative position with the rail B, after which the proper rail-securing mechanism is fitted to hold said rail.

In making the rails fast to a rail-block or tie, lead washers 11 are placed on the bolts to engage the face of the tie and also the shoulders 5 against which the heads of said bolts are anchored, and to insure a speedy and accurate attachment of the rail when properly aligned, the washers, a plate 13 and also a locking nut 12 are placed on a bolt before being slid to position against a rail, after which the nut 12 is run on the bolt to firmly impress the lead washers against the interlocked walls of the tie which they engage. The bolts 1 are threaded to extend above the anchor nuts 12 when the latter are properly screwed in place to afford the attachment for rail clamps E and clamp nuts 14. Preferably the rail securing clamps E have shanks with holes 15 corresponding in shape to the anchor nuts over which they are placed when in operative position, said clamps preventing said anchor nut from turning on its bolt when a clamp is fitted to a rail flange, the nut 14 being run on the upper extremity of the bolt 1 to hold the clamp firmly on and against the rail.

Aside from a clamp engaging the flange of a rail from its upper surface, provision is afforded to keep said clamp from rolling sidewise by forming a shoulder (as 16) adapted to bear against the edge of a rail. Should a clamp become loosened, either by a loosening of its nut 14 or by the wear of the rail seat lowering the rail, said clamp would not turn on its bearing nor recede from said rail and endanger the stability of its anchor bolt by loosening its nut.

Ties made in the manner herein described can be used to great advantage in yards where the tracks are run-in angles to other

lines, and especially where switches are installed, as by the provision of securing the rails at other than predetermined points a line of track may be placed where needed and the clamps attached to meet track exactions.

We are aware that in lieu of lead washers for preventing the anchor bolts from moving when seated, spring washers and nuts might be used, but in using washers of lead the nature of the material permits the bolts to be very firmly anchored, as washers of lead impress the roughened surface of concrete or metal and prevent slippage when anchored, and lead will not deteriorate and become useless as would washers of fibre or some metals.

From the foregoing explanation of our improved tie it is believed its operation and advantages will be fully comprehended.

Having, therefore, set forth our invention, what we claim as new and desire to secure by Letters Patent, is:

1. A railway tie having a longitudinal slot with oppositely-disposed side offsets and formed with end openings co-incident with said side offsets, bolts having heads adapted to be lowered into said end openings and be moved into said slot with said heads abutting shoulders formed by said offsets, washers placed on said bolts over their free extremities, anchor nuts run on the threaded ends of said bolts against said washers and clamping said bolts to said tie, clamping members placed on said bolts over said anchor nuts and nuts run on said bolts to secure said clamps, in combination with a T-rail the flange of which crosses said tie between said bolts and is impressed between said clamping members and said tie.

2. A railway tie having a longitudinal slot therethrough from bottom to top and formed with oppositely-disposed central offsets, said slot having end openings corresponding in breadth to the width of said slot and its offset openings, bolts having heads adapted to be lowered into said end openings and to be moved into said slot with said heads abutting shoulders formed by said offsets, washers placed on said bolts over their free extremities, anchor nuts run on the threaded ends of said bolts against said washers and clamping said bolts to said tie, clamping members placed on said bolts over said anchor nuts and nuts run on said bolts to secure said clamps, in combination with a T-rail the flange of which crosses said tie between said bolts and is impressed between said clamping members and said tie.

3. The combination with a railway tie having a longitudinally-formed slot and a railway rail crossing said tie, a bolt screw-threaded at one end and headed at its opposite end operative within said slot either

side of said rail, with its threaded end projecting from said slot, soft metal washers carried by each of said bolts adapted to engage said tie both at the threaded and headed ends of said bolts, hard metal plates carried by said bolts at their threaded ends, nuts run on the threaded ends of said bolts over said plates, clamps carried by said bolts over said nuts and engaging the side flanges of said rail, and nuts run on the free ends of said bolts and on said clamps, substantially as and for the purpose set forth.

4. The combination of a railway tie having a longitudinal vertically-disposed slot, anchor bolts threaded at one end and headed at the opposite end placed in said slot, lead washers strung on said bolts, anchor plates strung on said bolts over said washers, anchor nuts run on said bolts above said plates, said washers arranged to engage said tie and adapted to engage said tie both between the heads of said bolts and their nuts, said anchor nuts adapted to be run on said bolts to secure said tie between said lead washers.

5. The combination with a railway tie, of anchor bolts extending from said tie and longitudinally adjustable therewith, anchor nuts run on said bolts on the face of said tie, rail clamps fitted on said bolts above said anchor nuts and clamp nuts run on said bolts over said clamps.

6. The combination with a railway tie and a rail crossing said tie, of anchor bolts either side of said rail adjustably fitted within said tie and adapted to be moved together with said rail along said tie, anchor nuts run on said bolts on the face side of said tie, rail clamps fitted on said bolts above said anchor nuts and bearing on said rail, and clamp nuts run on said bolts over said clamps to secure said rail.

7. The combination with a railway tie, of anchor bolts extending from said tie, anchor nuts run on said bolts to impress said tie, rail clamps fitted on said bolts above said anchor nuts, said clamps having sockets adapted to receive said anchor nuts, and clamp nuts run on said bolts above said clamps to impress said clamps.

8. The combination with a railway tie and a rail crossing said tie, of adjustably fitted anchor bolts extending from said tie at either side of said rail, anchor nuts run on said bolts adapted to impress said tie, clamps fitted on said bolts over said anchor nuts engaging the flanges of said rail, said clamps having depending shanks with sockets adapted to receive said anchor nuts, said clamps having shoulders adapted to engage the edges of said rail flanges to prevent said clamps from turning, and clamp nuts run on said bolts to secure said clamps on said flanges.

9. The combination with a railway tie

- 4
- having a longitudinal slot, of anchor bolts headed at one end and screw-threaded at their opposite ends portably operative within said slot with said threaded ends extending beyond said slot, soft metal washers run on said bolts engaging opposite faces of said tie between the head and the threaded ends thereof, and nuts run on the threaded ends.
10. The combination with a railway tie having a longitudinal slot, of anchor bolts headed at one end and screw-threaded at their opposite ends portably operative within said slot with said threaded ends extending above said tie, soft metal washers run on said bolts engaging opposite faces of said tie between the head and threaded ends thereof, and nuts run on their threaded ends, and rail clamping members fitted on said bolts over said nuts.
15. 11. The combination with a railway tie and a rail clamping bolt removably fitted therein, said bolt being screw-threaded at an end extending above said tie, means to anchor said bolt within said tie, a lead washer carried by said bolt at its threaded end, a hard metal plate carried by said bolt over said washer, and a nut run on said bolt and adapted to bear upon said plate and impress said washer on said tie.
20. 12. The combination with a railway tie

having a longitudinal slot, a rail-clamping bolt headed at one end and screw-threaded at its opposite end operative within said slot with the threaded end extending beyond said slot, lead washers carried by said bolt both at its headed and threaded ends and adapted to engage said tie between the headed and threaded ends thereof, a hard metal plate carried by said bolt over the lead washer at its threaded end, and a nut run on said bolt at its threaded end and adapted to impress said plate.

13. The combination with a railway tie having a longitudinal slot, a rail clamping bolt headed at one end and screw-threaded at its opposite end operative within said slot, hard metal plates carried by said bolt at both its headed and threaded ends, lead washers carried by said bolt adapted to engage said tie between said plates, and a nut run on the threaded end of said bolt adapted to impress said tie between said lead washers, as and for the purpose set forth.

ROLAND V. RANDALL.
